ACIDPROOF TANK

Richard Neuhaus, Buffalo, N. Y., assignor to
Nukem Products Corporation, Buffalo, N. Y.,
a corporation of New York

Application July 15, 1935, Serial No. 31,393

11 Claims. (Cl. 72—14)

This invention relates to an acid-proof tank designed for pickling metal bars and more particularly to tanks of large size, tanks of this character being commonly several hundred feet long.

The present invention relates generally to the type of acid-proof tank as shown in my prior Patent No. 1,847,192 in which the tank is formed by providing an outer concrete shell, the inner surface of which is coated with asphalt and the tank then lined with acid-proof bricks set up in sulfur cement, the molten sulfur cement being poured between the joints of the bricks as they are set up in the manner disclosed in my said patent. With such tanks the asphalt layer between the outer shell and the inner shell serves two functions, first, that of providing a cushioning layer which permits the inner shell to expand relative to the outer shell, and second, that of providing a sealing layer which intercepts any acids that may seep through hairline cracks of the lining shell and prevent them from attacking the concrete shell. However, it has been discovered that when such tanks are built outdoors and when they are suddenly filled with hot acids after being subjected to low temperature weather conditions the expanding pressure of the inner shell is sufficient to actually break the outer concrete shell. This is due, of course, to the fact that at such low temperatures the asphalt cushioning layer is hard and does not yield and consequently the expanding force of the inner shell is transmitted directly to the outer shell with resultant breakage. Tanks of this character are made very much longer than they are wide and the difficulty does not arise in a direction transversely of the tank. However, with the extreme length of the tanks a breaking in two of the outer shell, as described, is liable to occur under cold weather conditions.

It is accordingly the principal object of this invention to provide a tank in which the inner shell is entirely free to expand lengthwise of the outer shell wholly independently thereof so that under no condition of operation can the outer shell be strained to the point of breaking.

It has also been discovered that with some tanks lined with a double course of brick and sulfur cement and having a cushioning layer of asphalt, an oozing of the asphalt through the wall lining is liable to occur. This oozing of the asphalt cushioning layer into the tank is due to minute hairline cracks which are liable to develop in the asphalt and brick lining and is highly objectionable as even a small quantity of asphalt in the tank will soil the metal sheets so that they

have to be rejected and re-cleaned. It has further been discovered that this oozing of the asphalt in the side walls always occurs in a zone not exceeding 15 inches from the bottom of the tank. This appears to be true regardless of the depth of the tank. Accordingly, the present invention proposes to place an additional wall of brick and sulfur cement around this zone, this wall extending no higher than 20 inches from the bottom of the tank around those walls which are asphalt backed and preventing the oozing of the asphalt into the tank.

In the accompanying drawing:

Fig. 1 is a top plan view of a tank embodying my invention.

Figs. 2 and 3 are enlarged vertical sections, taken on the correspondingly numbered lines on Fig. 1.

Fig. 4 is a horizontal section through one corner of the tank.

In accordance with the present invention the concrete shell 10 of the tank is first constructed. The bottom of the shell 10 is formed at one end to provide a depression 11, the depth of which is approximately equal to the smallest dimension of the bricks which are used in constructing the inner shell. At opposite sides of this depression 11 the side walls are offset outwardly as indicated at 12 so as to form pockets in the side walls, which pockets are approximately as wide as the width of the brick used in constructing the inner shell.

The concrete shell as thus constructed is then coated throughout with an inner layer 13 of asphalt.

After being so coated a layer of bricks 14 is laid in the depression 11, the upper flat faces of these bricks being substantially coplanar with the bottom of the concrete shell 10. These bricks 14 are preferably laid in break-joint relation and the joints between them are filled with sulfur cement 15. A wall of acid-proof bricks 16 are then laid around three edges of the layer of bricks 14 and against the corresponding walls of the concrete shell 10. The wall 16 is preferably only a single brick thick and after each course is laid suitable forms are provided against the inside face of the course and molten sulfur cement 17 is poured between the bricks forming the course in the manner disclosed in my prior Patent No. 1,847,192. The wall of bricks 16 fills the pockets 12 in the side walls of the concrete shell and lines the adjacent end wall of the tank, as best illustrated in Fig. 1. As previously stated the bricks 16 forming the side walls fill the pockets 12 so as to bring

the interior of the tank into rectangular form. A wall of bricks 20 set in sulfur cement 21 is then erected. This wall is arranged transversely of the tank and is spaced a short distance from the 5 end wall formed by the bricks 16 so as to provide an expansion chamber or gap 22. The wall formed by the bricks 20 extends the complete width of the tank and at its opposite ends is united to the side walls formed by the bricks 16 10 by the sulfur cement 21 in which the bricks 16 are laid.

The exposed upper surface of the bricks 14 are then coated with a layer of asphalt 23, this layer forming a continuation of the asphalt 13 on the 15 bottom of the concrete shell and the inside face of the side walls formed by the bricks 16 are then coated with a layer of asphalt 24, this asphalt 24 forming a continuation of the asphalt 13 on the side walls of the concrete shell, as best 20 illustrated in Fig. 1.

The lining of the tank then proceeds in the manner disclosed in my prior Patent No. 1,847,192, a layer of acid-proof bricks 25 being placed over the layer of asphalt 13 and 23 on the 25 bottom of the tank and the joints between these bricks being filled with sulfur cement 26. After this additional layers of bricks 27 and 28 are placed in position and each separately filled with molten sulfur cement, as best illustrated 30 in Fig. 2. The lining of the side walls then proceeds, a double course of brick 29 being first laid around the inside of the tank against the walls of the concrete shell 10 and against the side 35 walls formed by the bricks 16 and the end wall formed by the bricks 20. The walls are then built up course upon course until the top of the concrete shell is reached, each course having its joints filled with molten sulfur cement before 40 the next course is laid and a suitable form or strip or paper being provided against the inside of each course to retain the molten sulfur cement until it has hardened.

It will be understood that in providing the 45 horizontal joints between the several courses that type of brick can be used which is provided with small feet for this purpose or small pieces of hard sulfur cement can be placed under each brick as it is laid so as to provide a space under 50 it to receive the molten sulfur cement.

With a tank constructed as above described it is apparent that the space 22 permits of free 55 expansion and contraction of the bricks and sulfur cement lining lengthwise relative to the concrete shell 10, the entire end wall formed by the bricks 20 being moved bodily as the lining expands and contracts. While the sulfur cement which joins the bottom and sides of this 60 wall to the side walls formed by the bricks 16 and the bottom formed by the bricks 14 is necessarily broken in the initial expansion of the tank, this sulfur cement remains sufficiently intact so as 65 to form a barrier against the seepage of the asphalt layers 24 into the chamber 22 which, of course, if it occurred in a large degree would defeat the principal object of the invention. While a small amount of acid may seep through 70 to this small space 22 this acid does not, of course, interfere with the free movement of the end of the lining of the tank into this space regardless of how cold it may be.

It will also be noted that the concrete shell 75 of the tank is protected throughout by an asphalt cushioning layer so that acid from the tank cannot seep through and disintegrate the con-

crete shell, the asphalt operating to seal any hairline cracks which might develop. It will also be observed that at the end of the tank where expansion is provided for, double asphalt layers are provided at the places where seepage of acid 5 would be most likely to occur, i. e. the end of the lining shell which moves under expansion and contraction forces. Thus acid seeping through to the expansion chamber 22 is prevented by the asphalt layers 23 and 24 from seeping under 10 or around the moving end of the lining shell to the concrete shell and is prevented by the asphalt layer 13 from seeping out through the courses of bricks of single thickness which line this expansion chamber. 15

With concrete shells lined with side walls of two thicknesses of brick, set in sulfur cement, as previously described, it has been discovered that hairline cracks will occasionally develop in the walls which permit a small amount of asphalt to ooze through the brick lining and into the tank. Such oozing is particularly objectionable because the asphalt will settle on the sheets and soil them so that they have to be rejected and recleaned and if the soiling is not discovered while the sheets are being removed from the tank, subsequent imperfect processing of the sheet may require it to be scrapped. It has further been discovered that regardless of the height of the walls of the tank, these cracks always develop within a zone not exceeding 15 inches from the bottom of the tank. Therefore as an additional protection against such oozing of the asphalt as above described, those walls of the tank which are backed by the asphalt cushioning layer 13 are faced with a low wall of bricks 31. The bricks forming this low wall are set in sulfur cement 32 and are bonded to the wall which they face by sulfur cement. This low wall is preferably not more than 20 inches 30 high and terminates a substantial distance below the normal level of the liquid in the tank and is less than half the height of the tank. To carry it higher would not only be a needless waste of material but would also reduce the size of the tank which the low wall of brick does not and the low wall has been discovered to completely protect the zone in which oozing out of the asphalt is liable to occur. In the construction of 35 tank shown only the walls of the true inner lining shell are backed by an asphalt layer and consequently the low wall of brick 31 extends around these three walls only. If the tank were not provided with an expansion space, but lined, for example, as shown in my said Patent No. 1,847,192 then, of course, the low wall would be provided around all four side walls of the tank. 40

From the foregoing it is apparent that the present invention provides a tank lined with acid-proof brick and sulfur cement in which the lining is entirely free to expand lengthwise of the tank to avoid breaking the concrete shell in two as has occurred heretofore. Further, by the provision of the space 22 for this expansion all expanding strains due to the differences in coefficients of expansion between the shell and the lining are relieved so that cracks are less likely to develop and the tank will have an indefinite life. Further, in the provision of the space 22 to 45 permit this expansion adequate means are provided for preventing asphalt from entering the space and also adequate protection is afforded against such acid as may enter this space from attacking the concrete shell inasmuch as the 50 55 60 65 70 75 80 85 90 95

bottom layer of bricks 14 and the walls formed by the bricks 16 are laid against a layer of asphalt which will repel any acids which may seep through these bricks. Further, the present invention provides additional protection at the zone where hairline cracks are liable to develop and permit oozing out of asphalt, namely within 15 inches from the bottom of the tank, without decreasing the effective size of the tank and without 10 requiring the use of an undue quantity of brick and sulfur cement for this purpose.

I claim as my invention:

1. An acid-proof tank of the character described, comprising an outer shell, an inner shell 15 composed of brick and sulfur cement and a lining of asphalt between said inner and outer shells, said shells being constructed to provide an air space therebetween to permit expansion of the inner shell relative to the outer shell.

20 2. An acid-proof tank of the character described, comprising an outer shell, an inner shell comprised of brick and sulfur cement, said shells being constructed to provide a space therebetween to permit expansion of the inner shell relative to the outer shell, a lining of asphalt between 25 said inner and outer shells, and a wall arranged within said space for supporting said lining of asphalt, said last wall being spaced from said inner shell.

30 3. A tank of the character described, comprising an outer shell, a lining of asphalt lining said outer shell, an inner shell composed of brick and sulfur cement, said shells being constructed to provide a space therebetween to permit expansion 35 of the inner shell relative to the outer shell, and a wall of acid-proof material arranged within said space for supporting said lining of asphalt, said wall being spaced from said inner shell and being extended laterally inward at its bottom to extend under the inner shell.

40 4. A tank of the character described, comprising an outer shell, a layer of asphalt lining said outer shell, an inner shell composed of brick and sulfur cement, said shells being constructed to provide a space therebetween to permit expansion 45 of the inner shell relative to the outer shell, a wall of acid-proof material arranged within said space for supporting said layer of asphalt, said wall being spaced from said inner shell and being extended laterally inward at its bottom to extend under the inner shell and a layer of asphalt between said inner shell and that portion 50 of said wall extended thereunder.

5. An acid-proof tank, comprising an elongated outer shell and an elongated inner shell composed of brick and sulfur cement and having a bottom resting on the bottom of said outer shell, and having two side walls and one end wall supported against the corresponding walls of said outer shell, the other end wall of said inner shell being spaced from the corresponding end wall of said outer shell, said space permitting lengthwise expansion of said inner shell relative to said outer shell.

6. An acid-proof tank, comprising an elongated outer shell, an elongated inner shell composed of brick and sulfur cement and having a bottom resting on the bottom of said outer shell, and having two side walls and one end wall supported against the corresponding walls of said outer shell, the other end wall of said inner shell being spaced from the corresponding end wall of said outer shell, said space permitting lengthwise ex-

pansion of said inner shell relative to said outer shell and a layer of asphalt between said shells.

7. A tank of the character described, comprising an elongated outer shell, a layer of asphalt on the inside of said outer shell, a wall composed of brick and sulfur cement arranged against the inner face of one end wall, an elongated inner shell composed of brick and sulfur cement and having a bottom resting on the bottom of said outer shell, and having two side walls and one end wall supported against the corresponding walls of said outer shell, the other end wall of said inner shell being spaced from said first named wall to provide a clearance space permitting expansion of said inner shell relative to said outer shell.

8. An acid-proof tank of the character described, comprising an elongated outer shell having its side walls offset laterally at one end to provide interior pockets therein and also having its bottom formed to provide a depression between said pockets, a layer of asphalt over the inner surface of said outer shell, a layer of brick and sulfur cement in said depression, side walls of brick and sulfur cement in said pockets and an end wall of brick and sulfur cement connecting 25 said brick and sulfur cement side walls and disposed against the inner face of the adjacent end wall of said shell, said bottom layer and side walls of brick and sulfur cement forming coplanar continuations of the corresponding inner surface of said outer shell, and an inner lining of brick and sulfur cement within said shell, one end wall of said lining being spaced from said end wall of brick and sulfur cement to provide 30 a space permitting expansion of said lining lengthwise relative to said outer shell.

9. A tank composed of an outer shell including a bottom and side walls, a lining of asphalt over the inner surface of said outer shell, an inner lining shell including a bottom and side walls 40 of brick and sulfur cement and an additional wall of brick and sulfur cement erected against the inner face of at least one wall of said lining shell and having a height less than half the height of the walls of said lining shell and preventing oozing of said asphalt into the interior 45 of the tank.

10. A tank composed of an outer shell including a bottom and side walls, a lining of asphalt over the inner surface of said outer shell, an inner 50 lining shell including a bottom and side walls of brick and sulfur cement and an additional wall of brick and sulfur cement erected against the inner face of at least one wall of said lining shell and extending upwardly to a level substantially 55 below the normal level of the liquid in the tank and preventing oozing of said asphalt into the interior of the tank.

11. An acid-proof tank of the character described, comprising an outer shell, an independent inner shell built up of brick and sulfur cement within said outer shell and having a different coefficient of expansion from said outer shell, said inner shell being unconnected with said outer shell, the horizontal outer dimensions of said inner shell being less than the corresponding internal dimensions of said outer shell thereby to provide an air space open at its upper end and extending the fuel height of said inner shell to 60 permit expansion of said inner shell relative to said outer shell.

RICHARD NEUHAUS.
